UNITED STATES PATENT OFFICE.

AUSTEN H. FOX, OF NEW YORK, AND ARNOLD W. LENDEROTH, OF STAPLETON, NEW YORK.

PERMISSIVE AUTOMATIC TRAIN-STOP.

1,223,685.

Specification of Letters Patent. Patented Apr. 24, 1917.

Application filed April 21, 1913. Serial No. 762,462.

To all whom it may concern:

Be it known that we, AUSTEN H. FOX and ARNOLD W. LENDEROTH, citizens of the United States, residing at New York city, in the county and State of New York, and at Stapleton, in the county of Richmond and State of New York, respectively, have invented certain new and useful Improvements in Permissive Automatic Train-Stops, of which the following is a specification.

This invention relates to apparatus for automatically controlling railway trains, and its principal object is to provide means for rendering such a system permissive under certain conditions. While it has long been recognized as desirable to automatically stop a train, in case the engineer should not do so at a signal set against the train, there are also occasions when it is consistent with the requirements of safety to allow the train to pass a signal so set. Thus, the signal may be out of order and give a false indication of danger, in which case the train should be allowed to proceed into and through the danger block, but should be slowed down and brought under control as a precautionary measure. It is also considered safe to approach closely to a stalled or slow-moving train ahead, provided the following train is moving so slowly that it can be very quickly stopped if necessary.

An automatic stop which shall meet these conditions of railway operation must be permissive below a certain speed, and we have devised our present invention with the object of allowing the engineer on reaching a signal set at danger, to pass that signal at a predetermined slow speed—say ten miles an hour—and thereafter proceed through the block so long as he keeps below that speed. The system may be so arranged that the engineer must bring the train to rest (on penalty of being automatically stopped if he fails to do so) before entering the danger block, and it may be so devised as to require the coöperation of another person, such as the conductor, to place it in the permissive condition so that the train may proceed.

Our invention preferably includes provision for automatically removing the speed-limit on passing out of the block if the signal at the head of the next block is set at clear.

We prefer to employ our invention in con-

nnection with an electromagnetic detector apparatus for establishing communication between the moving unit and roadway, such for example as shown in the patent to A. H. FOX, No. 1,088,814, dated March 3, 1914, and in our co-pending application Serial No. 713,965, filed August 8, 1912, but it will be understood that the invention also applies to systems wherein the communication between vehicle and roadway is established mechanically or otherwise.

Of the accompanying drawings,

Figure 1 represents an end elevation, partly in section, showing speed-responsive devices constructed according to our invention.

Fig. 2 represents a top plan view thereof, partly in section.

Fig. 3 represents a diagrammatic view showing the electrical connections.

Fig. 4 is an elevation showing the position of the conductor's switch on the locomotive.

In the drawings, 10 represents the axle of the vehicle, on which is clamped a split drum or hub 11. 12 is a tripper-arm pivoted at 13 on said hub and having a laterally-acting cam 14 and a spring 15 which normally retracts said arm, the tension of the spring being such that when a predetermined speed (such as ten miles an hour for example) is attained by the vehicle, centrifugal force will act to throw the cam out into operative position.

Adjacent to the hub 11 there is mounted on a fixed bracket 16 an electromagnet in the form of a hollow coil 17 through which passes a soft-iron rock-shaft 18 having at its ends two soft-iron pole-pieces 19 which coöperate with the ends of an armature 20 attached to said fixed bracket. Also fixed to the shaft 18 are suitable switch members to be hereinafter described, and a pair of arms 21 carrying a square guide-rod 22. A spring 23 tends to rock the shaft 18 so as to draw the pole-pieces 19 away from the armature 20. The rocking parts are preferably balanced so that the axis of shaft 18 passes through their center of gravity.

On the guide-rod 22 is fixed an insulating block 24 carrying two pairs of switch-points or electrodes 25, 26, which coöperate with a conical block 27 slidably mounted on the guide-rod 22. The small end of this block is provided with a metallic bridging

contact 28, and the large adjacent portion is made of insulating material. The angle of block 27 is such that the spring of the electrodes 25, 26 normally forces said block to the right as viewed in Fig. 3 and causes the electrodes to rest on the bridging contact 28 and thus close the switch. The electrodes 25 and 26 we prefer to provide in duplicate on opposite sides of the bridging contact 28, so as to insure that any shocks shall not separate both electrodes of a pair at the same time. The hub of the block 27 is provided with an arm 29 carrying a roller 30 which is adapted to coöperate with the centrifugally-actuated tripper cam 14 when the speed exceeds the predetermined limit and the magnet coil 17 has been energized to bring said roller into the path of the cam.

At opposite ends of the rock-shaft 18 are two switches 31, 32 operated by the movement of said rock-shaft when the magnet is energized, the purpose of switch 31 being to maintain the closure of the magnet circuit, and the object of the switch 32 being to close a shunt circuit around the detector switches hereinafter described, which latter would ordinarily cause the automatic stopping of the train at a danger signal regardless of the speed of the train. Switch 31 includes a fixed insulating block 33 carrying two pairs of switch-points or electrodes 34, 35, a cylindrical insulating block 36 mounted on the rock-shaft 18, a metal ring 37 against which the electrodes 34 bear, and a pair of contact plates 38 (only one of which is shown) branching from the ring 37 and located in the path of the electrodes 35.

Switch 32 includes a fixed insulating block 39 carrying a pair of switch-points or electrodes 40, a cylindrical insulating block 41 on the rock-shaft 18, and a pair of bridging contacts 42 located on said block in the path of the electrodes 40 and electrically connected to each other as indicated in Fig. 1. The electrodes of these switches also are preferably duplicated on opposite sides of the rotary members to avoid the effect of shocks.

Referring now to Fig. 3, we have represented diagrammatically a track apparatus and an electromagnetic detector similar to that shown in our application Serial No. 713,965 aforesaid. 43 represents one of the running rails provided at a control point with a non-magnetic section 44 (preferably manganese steel), a pair of fixed magnetic bars 45, 46 overlapping the joints, and a movable magnetic bar or by-passing member 47 adapted when in its operative position to counteract the effect of the non-magnetic rail section 44, and when in its inoperative position adapted normally to produce the stopping effect on the train through the action of the detector apparatus. As here shown this by-passing bar 47 is adapted to be raised

and lowered by rock-arms 48 which may be connected with the signal apparatus.

49 is a detector magnet carried by the vehicle and comprising a coil through which passes a hollow magnetic rock-shaft 50 having on its ends two pole-pieces 51, and a second magnetic shaft 52 passing through the shaft 50 and having on its ends two pole-pieces 53. When the coil of magnet 49 is energized, these pole-pieces tend to be drawn angularly in opposite directions toward the magnetic parts of the running rail 43 and the track apparatus, and when a magnetic gap is reached, the respective pole-pieces at each end, being of like polarity, tend to repel each other, the oscillating parts being preferably mechanically balanced as represented in our aforesaid application Serial No. 713,965 (though not so shown here). The pole-pieces 53 coöperate principally with the inner half of the running rail, and the pole-pieces 51 with the outer half and with the bars 45, 46, 47.

The pole-pieces of magnet 49 control three detector switches, shown diagrammatically, these switches being closed when the pole-pieces are attracted. The switches 54, 55 at one end of the detector are in parallel with each other and in series with an electromagnet 56, hereinafter described, for holding closed a valve in the train pipe of the air-brake system. The switch 57 at the opposite end of the detector is for the purpose of clearing the apparatus by removing the speed limitation when the train enters the next block, if that block is clear.

58 is a telltale switch adapted to be opened by a spring 59 and closed by an armature 60 which responds to a magnetic condition of the detector magnet 49, the function of this switch being to open the circuit of the train-pipe magnet 56 and allow the brakes to be set if the energizing circuit of magnet 49 (which is kept constantly closed) should be broken.

61 is a portion of the train pipe having an outlet valve 62 attached to the armature 63 of the magnet 56 and held closed by the attraction of the latter. We prefer to provide switch-points 64 in series with this magnet and bridged by a contact on the armature 63, so that when said armature drops and opens the valve 62 (due ordinarily to a merely momentary break when the detector, which is self-restoring, passes a magnetic gap in the roadway), the valve shall remain open until restored by a suitable agency, for example the manual raising of armature 63.

65 is a suitable source of electrical energy such as a battery, 66 is a switch which we term for convenience a conductor's switch, and 66^a is a switch which may be termed the engineer's switch. The purpose of switch 66 is to place the apparatus in a permissive con-

dition before the train enters a danger block, and if it is planned that the train must be brought to a stop in order to accomplish this, we prefer to so locate said switch that it can be operated only by a person (such as the conductor) standing on the roadway, who has a key to unlock the switch. Thus we may place the switch 66 in a box 84 whose door has a key-operated lock 85, the said box being so located on the locomotive 86, as indicated in Fig. 4, that it may be reached by a person standing alongside. The purpose of switch 66^a is to retain the apparatus in its permissive condition when the detector is passing over a non-magnetic rail-section 44, whose by-passing rail 47 is depressed.

We will first trace the circuits whereby the detector normally operates to stop the train when a danger signal is passed. Coil 49 is connected in circuit with the battery 65 by main wires 67, 68. A parallel circuit is carried from wire 67 by wire 69, through the train-pipe magnet 56, its retaining switch 63, 64, and wires 70, 71, to the tell-tale switch 58, and from thence by way of wire 72, branching in parallel through the two detector switches 54, 55, and through wires 73 and 74 to the electrodes 25 of the speed-controlled switch. (The electrical connection to only one of the opposite duplicate electrodes of this switch and the switches controlled by coil 17 is shown in each case.) If this switch is closed, the current passes across the bridge contact 28 to the electrodes 26, and from thence by wires 75, 76 and 68 back to the other side of the battery. This circuit being complete when the detector is over a magnetic part of the running rail or is passing a control point where the track apparatus is set at clear, the magnet 56 will remain energized and the train pipe closed, but if both of the detector switches 54, 55 should be open as represented in Fig. 3, the train would then, if no other agency intervenes, be automatically stopped.

We will now trace the circuits for the self-retaining and by-pass switches, and the energizing circuit, of magnet 17. Current is led from the wire 67 through a wire 77 containing the conductor's switch 66, and thence through the winding of the magnet 17 and by way of wires 78, 76 and 68 to the opposite side of the battery. A parallel circuit is taken from the wire 67 by the wire 79 to the clearing switch 57, and thence by wire 80 to the electrodes 35 of the self-retaining switch 31, across the plate 38 (if said switch is closed), to ring 37, and thence out through electrodes 34 and a wire 81 to the wire 77 and on to the magnet 17 as described. Hence when the conductor's switch 66 is closed to energize magnet 17 and bring the roller 30 into the path of the centrifugal

trip-cam 14, a parallel circuit will thereby (if the detector pole-pieces 51 are attracted so as to close the switch 57) be closed through the self-retaining switch 31, and the magnet will remain energized when the conductor releases switch 66. To provide for keeping it energized at will when the detector is passing a magnetic gap in the running rail, the engineer's switch 66^a (located in an accessible position in the cab) is provided in a shunt 87 around the clearing switch 57.

If this shunt and engineer's switch were omitted, the switch 66 could be located in the cab (preferably without any box or key) and used as an engineer's switch, in which case the danger block could be entered at any speed below ten miles an hour by keeping switch 66 closed while passing the danger-set track apparatus.

The shunt circuit for by-passing the detector switches is carried from wire 70 by way of wire 82 to and through the by-pass switch 32 if the latter be closed, and from thence by way of wires 83, 74 to the speed-controlled switch 25, 26, 28; thence through said switch if the latter be closed, and by way of wires 75, 76 and 68 to the battery, it being observed that this path forms a direct circuit through the train-pipe magnet 56 around all the detector switches, and that the speed controlled switch 25, 26, 28 is in the return wire 74, 75, 76 from both the shunt 82, 83 and the detector switches 54, 55.

The operation of our invention is as follows: When the detector magnet 49 is over a magnetic part of the running rail, both sets of pole-pieces 51, 53 will be attracted, and the switches 54, 55, held closed. This energizes the air-brake magnet 56 and keeps the valve 62 closed, the circuit of said magnet being complete through the tell-tale switch 58 (which stays closed by magnetic attraction as long as the circuit of the detector magnet 49 remains intact), and the normally-closed speed-controlled switch 25, 26, 28. Switch 57 in the circuit of magnet-coil 17 being also held closed by the attraction of the running rail, this circuit is in condition to be completed through its branch 80, 81 by the self-retaining switch 31, or the circuit of coil 17 may be closed by way of the engineer's switch 66^a and switch 31 regardless of 57, after said coil has been energized by closing the conductor's switch 66.

Whenever the detector magnet passes over a non-magnetic rail-section 44, the switch 57 will be opened, and the switch 54 will also be opened, by the magnetic repulsion of the pole-pieces 51 exerted on the pole-pieces 53, but nevertheless if the magnetic filler 47 is raised into place (indicating a clear block), the pole-pieces 51 will remain attracted and their switch 55 closed, and therefore the air-brake valve 62 will remain closed. If, how-

ever, the bar 47 is dropped into inoperative position as represented in Fig. 3, which indicates a danger condition in the block at the entrance to which this track apparatus is located, both sets of pole-pieces 51, 53 will be released and repelled, and both switches 54, 55 opened. Thereby the circuit of the magnet 56 will be broken and the valve 62 will be opened to release air from the train-pipe 10 and cause the brakes to be set, provided the apparatus has not previously been placed in a permissive condition, and the train run into the block at a speed below the permitted maximum.

15 The permissive condition may be established by closure of the conductor's switch 66. In order to operate this switch the train must have been brought substantially to a stop so that the conductor may go forward 20 and unlock and open box 84 from the outside in order to reach said switch. This is done just before entering the danger block and while the detector is over a magnetic rail-section, so that the circuit through magnet 25 17, being closed at the switch 57, will remain closed through the self-retaining switch 31 when the conductor releases the switch 66. The engineer may now bring his train slowly into the danger block by keeping switch 66^a closed while the detector passes the magnetic gap, so as to avoid the effect of the momentary opening of switch 37 caused by the non-magnetic rail-section 44. He is enabled to enter, because the energizing of magnet 17 has closed the by-passing switch 32, whose members 40 and 42 are located in a shunt around the detector switches 54, 55, and the air-brake valve therefore remains closed even though both 30 of said detector switches have opened as the detector passes the magnetic gap produced by the rail section 44 and the retracted filler bar 47. But the attraction of the poles 19 for the stationary armature 20 of magnet 45 17 has also brought the roller 30 of the switch 25, 26, 28 into the path of the cam 14. Hence if the train should be going faster than the permitted speed on entering or passing through the block, or in fact at 50 any time after the permissive condition has been established as above described, and while it remains in force, the train will be automatically stopped, for the reason that cam 14, being projected by centrifugal force 55 into the path of roller 30, will open the switch 25, 26, 28, and thereby break the circuit of the air-brake magnet 56. Roller 30, after once being brought under command of the centrifugally-actuated cam 14, as above 60 described, is thereafter restored only by a non-magnetic rail section 44 acting to open the clearing switch 57.

If the signal and track apparatus at the entrance to the next block should also indicate a danger condition, but the condition

of the track in sight should warrant continuing to proceed under control, the train need not be brought to rest again, but must remain below the permitted maximum speed, and the block may then be entered 70 as before if the engineer closes his switch 66^a while passing the magnetically-open track apparatus. Should this signal and track apparatus however be set at "clear", with bar 47 raised into operative position, 75 the engineer's switch should not be operated. On entering the block, the non-magnetic rail-section 44 opens the clearing switch 57 and breaks the circuit of magnet 17, and the train may then proceed through 80 the block at any speed.

A railway company using this system may consider it necessary only to have the train brought under control before entering a danger block, and not actually stopped, and 85 in that case, as above mentioned, switch 66 may be located in the cab and used as the engineer's switch in place of switch 66^a.

In our Patent No. 1,007,192 is described a detector apparatus included in, or operating 90 in conjunction with speed-controlled devices; and there, as in the present case, the effect of the detector is counteracted below a certain speed—or in other words, the system is permissive in its operation. In that patent we 95 illustrated means in the roadway for selecting or determining the permitted speed, so that certain speeds must not be exceeded at certain points such as curves, bridges, etc., and the permitted maximum might be different at different control points, without however any provision of means to prevent the engineer from speeding up after passing the control point. In our present invention 100 it will be noted that provision has been made for allowing a person or persons to place or maintain the apparatus in its permissive condition (or suffer the penalty of being stopped for failure to do this on entering a danger block), and for causing that 105 condition to persist until a further event happens, such as the train passing out of the danger block into a clear block.

Obviously, by describing a magnetic detector and electrical circuits, a roadway control apparatus in and adjacent to the track rather than somewhere else on or about the roadway, and certain arrangements of circuits and circuit devices as the preferred embodiment of our invention, it is not to be 110 understood that we are wholly confined to expedients of this particular nature, or class, or to the employment of the entire invention in one system. Furthermore, it is well known that any automatic train-control device of this general class may give merely a cab-signal instead of actually stopping or slowing the train by means of the air-brakes or other agency, and we comprehend 115 these various possible functions of our de- 120 125 130

tector under the general expression "giving an indication" on the vehicle.

We claim:

1. Train-control apparatus comprising a vehicle having a detector responsive to the condition of the roadway, a stopping device controlled by said detector, a speed-responsive member, means controllable by a person and also controlled by said member for avoiding the normal effect of the detector on said stopping device below a predetermined speed at control points in the roadway, and a device actuated concurrently with the last-said means on assuming its operative condition for retaining it in that condition. 70
2. Train-control apparatus comprising a vehicle having a detector responsive to the condition of the roadway, a stopping device controlled by said detector, a speed-responsive member, means controllable by a person and also controlled by said member for avoiding the normal effect of the detector on said stopping device below a predetermined speed at control points on the roadway, an automatic self-retainer for holding said means in its operative condition, and a device on the vehicle responsive to the condition of the roadway for restoring said means to inoperative condition. 75
3. Train-control apparatus comprising a vehicle having a detector responsive to the condition of the roadway, a stopping magnet having a detector-controlled switch in its circuit, a speed-controlled switch in series with said magnet and detector switch, and a shunt circuit and means for closing the same around said detector switch. 80
4. Train-control apparatus comprising a vehicle having a detector responsive to the condition of the roadway, a stopping magnet having a detector-controlled switch in its circuit, a shunt circuit adapted to be closed around said detector switch, a magnet controlling the closure of said shunt circuit, and a speed-controlled switch located in the return from said detector switch and said shunt. 85
5. Train-control apparatus comprising a vehicle having a detector responsive to the condition of the roadway, a stopping device controlled by said detector, a speed-responsive member operative above a predetermined maximum speed of the vehicle, means for avoiding the normal stopping effect of the detector, and mechanism conjointly operative with said means for subjecting the connection between said detector and stopping device to the action of said speed-responsive member. 90
6. Train-control apparatus comprising a vehicle having a detector responsive to the condition of the roadway, a circuit having a stopping magnet and a detector-controlled switch, a speed-responsive member operative above a predetermined maximum speed of the vehicle, a switch in a shunt around the detector switch, a speed-controlled switch in series with said magnet and detector switch, and means controllable by a person for conjointly closing said shunt switch and subjecting the speed-controlled switch to the action of said member. 95
7. Train-control apparatus comprising a vehicle having a detector responsive to the condition of the roadway, a stopping device controlled thereby, a speed-responsive cam, a switch having an actuator movable into and out of the path of said cam and controlling the stopping device, and means positionable conjointly with said actuator for avoiding the normal stopping effect of the detector at speeds below the tripping speed of the cam. 100
8. Train-control apparatus comprising a vehicle having a detector responsive to the condition of the roadway, a stopping device controlled thereby, means subject to the speed of the vehicle for avoiding the normal stopping effect, mechanism for rendering said means operative at will, and a detector-controlled device for restoring said means to inoperative condition. 105
9. Train-control apparatus comprising a vehicle having a detector responsive to the condition of the roadway, a stopping device controlled thereby, means including a magnet whose circuit is controllable at will for avoiding the normal stopping effect at speeds below a predetermined maximum, a speed-responsive member operative at speeds above said maximum for controlling the connection between the detector and the stopping device, a self-retaining switch operated by said magnet, and a detector-controlled clearing switch controlling the circuit of said magnet. 110
10. Railway apparatus comprising a vehicle having a detector responsive to the condition of the roadway, an indicating device on the vehicle controlled by said detector, means responsive to the speed of the vehicle for avoiding the indicating effect of said detector at speeds below a predetermined maximum, and means on the vehicle within reach of a person standing on the ground for rendering the speed-controlled means operative. 115
11. Railway train-control apparatus comprising a vehicle having a detector responsive to the condition of the roadway, a stopping device controlled thereby, means controlled by the speed of the vehicle for avoiding the stopping effect at speeds below a certain maximum, a magnet for placing said means in an operative condition, and a switch located on the vehicle in position to be operated by a person standing on the ground, for controlling the circuit of said magnet. 120
12. Railway train-control apparatus comprising a vehicle having a detector responsive to the condition of the roadway, a stopping device controlled thereby, means controlled by the speed of the vehicle for avoiding the stopping effect at speeds below a certain maximum, a magnet for placing said means in an operative condition, and a switch located on the vehicle in position to be operated by a person standing on the ground, for controlling the circuit of said magnet. 125
13. Railway train-control apparatus comprising a vehicle having a detector responsive to the condition of the roadway, a stopping device controlled thereby, means controlled by the speed of the vehicle for avoiding the stopping effect at speeds below a certain maximum, a magnet for placing said means in an operative condition, and a switch located on the vehicle in position to be operated by a person standing on the ground, for controlling the circuit of said magnet. 130

- prising a vehicle having an electro-magnetic detector responsive to the magnetic condition of the roadway, track apparatus controlling the same and having danger and clear conditions, a stopping device controlled by said detector, means controlled by the speed of the vehicle for avoiding the normal stopping effect at speeds below a predetermined maximum, said means having an operating magnet, a retaining switch operated by the latter and a detector-controlled switch, both in circuit with said magnet, a conductor's switch accessible to a person standing on the ground for energizing said magnet and thus closing the retaining switch, and an engineer's switch for maintaining the magnet-circuit closed when the detector-controlled switch opens in passing a track-apparatus set in the danger condition.
13. Railway train-control apparatus comprising a vehicle having a detector responsive to the condition of the track, a track having detector-controlling means at the ends of signal blocks, a circuit on the vehicle having a stopping magnet and a detector-controlled switch, a speed-responsive cam, a second magnet, a by-passing switch in a shunt around said detector switch and a retaining switch both controlled by said second magnet, a speed-controlled switch in the return from said detector switch and shunt, having an actuator adapted to be positioned by the second magnet in the path of said cam when the by-passing and retaining switches are closed, and a clearing switch operated by the detector for opening the circuit of the second magnet as the vehicle passes from a danger block into a clear block.
